UNITED STATES PATENT OFFICE.

CHARLES H. BEELER, JR., OF PHILADELPHIA, PENNSYLVANIA, ASSIGNOR
TO MACKELLAR, SMITHS & JORDAN, OF SAME PLACE.

DESIGN FOR A FONT OF PRINTING-TYPE.

SPECIFICATION forming part of Design No. 15,811, dated February 17, 1885.

Application filed July 25, 1884. Term of patent 7 years.

To all whom it may concern:

Be it known that I, CHARLES H. BEELER, Jr., (assignor to MACKELLAR, SMITHS & JORDAN,) of the city and county of Philadelphia, Pennsylvania, have invented and produced a new and original Design for a Font of Printing-Type, of which the following is a specification.

The nature of this invention consists in the design hereinafter shown, described, and claimed.

The letters are fully illustrated in the accompanying impression. To the bottom and left hand of the letters are ornamental lines of shading. Between these lines and letters is left a space, which shows white between the black lines of the shading and the solid black of the letters. The lines of shading are about at an angle of forty-five degrees, running ob-

liquely down to the left from the letters, said lines being parallel. By this ornamentation the letters appear as though they were printed in blocks having white tops and their edges striated with black lines.

The same design is applied to numerals, as shown.

I am aware of a font of type in which horizontal lines of lower and left-hand shading are drawn touching the letters; but this I do not claim.

What I claim is—

The design for a font of printing-type, as herein shown and described.

C. H. BEELER, JR.

In presence of—

C. F. HUCH,
Jos. J. MURPHY.
